CAN CARRYING CART

Charles H. Krueger, Jr., 325 Edgewater Drive,
Mishawaka, Ind.

Filed Oct. 8, 1964, Ser. No. 82,096

Term of patent 14 years

(Cl. D14—3)

FIG. 1

FIG. 2

FIG. 3

I claim:

The ornamental design for a can carrying cart, substantially as shown and described.
